UNITED STATES PATENT OFFICE.

RUDOLPH HOFFMAN, OF CHICAGO HEIGHTS, ILLINOIS, ASSIGNOR TO SEARS, ROEBUCK AND COMPANY, OF CHICAGO, ILLINOIS, A CORPORATION OF NEW YORK.

BLUE-FLAME OIL-BURNER.

1,192,199.

Specification of Letters Patent. Patented July 25, 1916.

Application filed May 26, 1915. Serial No. 30,488.

To all whom it may concern:

Be it known that I, RUDOLPH HOFFMAN, a citizen of the United States, residing at Chicago Heights, in the county of Cook and State of Illinois, have invented certain new and useful Improvements in Blue-Flame Oil-Burners, of which the following is a specification.

This invention relates to hydrocarbon burners of the type in which concentric upright perforated combustion tubes are employed to produce a blue flame. The tubes are rigidly secured together and rest loosely upon a burner bowl containing a suitable wick. Surrounding the perforated tubes is a drum or chimney. When the burner is to be lighted the combustion tubes and the drum must be tilted to permit access to the wick. To support the drum and to permit of tilting the perforated tubes and the drum as a unit, it is necessary that there be some connection between the combustion tubes and the drum. It is, however, desirable that the drum be readily removable from the combustion tubes for convenience in cleaning or in replacing any of the parts.

The object of this invention is to provide improved means whereby the combustion tubes and the drum may be tilted as a unit although permitting the drum to be freely and easily withdrawn when desired.

In the accompanying drawings, Figure 1 is a vertical central sectional view through a burner embodying the features of my invention. Fig. 2 is a top plan view.

In the drawings 1 and 2 indicate the inner and outer perforated combustion tubes. Said tubes may be of any preferred construction and may be rigidly secured together in any ordinary or desired manner. Herein I have shown two pins 3 extending through both of the combustion tubes at right angles to each other, said pins serving to fasten the tubes rigidly together. The combustion tubes 1 and 2 are adapted to be supported upon a burner bowl 4 which may be of any suitable construction.

5 indicates the wick.

The drum or chimney 6 may be of any desired form. Herein it is shown as being of

generally frusto-conical shape, its lower larger end being provided with an annular inwardly-extending flange 7. The drum 6 is supported concentrically with the tubes 1 and 2 by means of a plurality of brackets 8 fixed to the outer tube 2 and projecting outwardly therefrom to engage in an annular groove 9 in the drum. In the present instance three of these brackets are provided and are spaced equi-distant around the tube 2, each bracket comprising a piece of sheet metal bent into U-form and having its ends fixed to the outer side of the tube 2, the apex of the bend engaging in the groove 9. When it is desired to disassociate the drum from the tubes, the drum is forced upwardly out of engagement with the brackets 8, the parts yielding to permit the apex of each bracket to be disengaged from the groove 9.

10 is a handle secured to the outer side of the drum and providing means for tilting the drum and the tubes, as indicated in Fig. 1, so as to give access to the wick for lighting the same.

I claim as my invention:

An oil burner having, in combination, an inner and an outer combustion tube rigidly secured together, a drum surrounding said tubes and having an interior annular groove, and a plurality of brackets spaced around the periphery of the outer tube, each bracket formed of a strap member comprising a U-shaped body portion and end portions bent at an angle to the U-shaped body portion and rigidly fixed in a vertical position to the outer side of the outer tube between the ends thereof, the middle body portion of each bracket being arranged to project from the side of the outer tube and to frictionally engage in said groove in the drum, the engagement of said brackets and groove being capable of being broken by forcing the drum upwardly, whereby the latter may be disassociated from the combustion tubes.

In testimony whereof, I hereunto set my hand in the presence of two witnesses.

RUDOLPH HOFFMAN.

In the presence of—

FRED LUNDSTROM,
E. H. SIEKMANN.
